C. E. SMITH

AMALGAMATING MACHINE

Filed Sept. 28, 1925

Patented June 7, 1927.

1,631,434

UNITED STATES PATENT OFFICE.

CHARLES E. SMITH, OF AZUSA, CALIFORNIA.

AMALGAMATING MACHINE.

Application filed September 28, 1925. Serial No. 59,079.

My invention relates to amalgamating and concentrating machines, and the objects are to provide an efficient, simple and effective machine to amalgamate and concentrate gold from ores from a mill or placer bed.

Other objects and advantages will be made manifest in the following specification for an embodiment of the invention, illustrated in the accompanying drawings, in which:

10 Figure 1 represents a longitudinal side elevational view of my machine.

Figure 2 represents a plan view of Figure 1.

15 Figure 3 is a sectional view taken on line 3—3 of Figure 2.

Figure 4 is a fragmentary side view of the riffle plates shown in Figure 1, taken on line 4—4 thereof.

20 Figure 5 is a fragmentary plan view of Figure 4.

Figure 6 is a sectional view taken on line 6—6 of Figure 2.

25 Figure 7 is a sectional view taken on line 7—7 of Figure 1.

Figure 8 is a diagram illustrating the lever adjustments of the sluice in my machine.

Referring to the drawings in which like characters of reference designate similar parts, my machine comprises a supporting frame 1 with a standard 10 positioned on the forward end thereof and the upright members 11 are positioned on the rear portion thereof. A set of bearings 6 and 7 are formed in the front—lower and upper—rear portions of said upright members 11, there being shafts 12 and 15 rotatably bearing in said bearings 6 and 7 respectively. A set of supporting links 4 and 5 are secured to the shafts 12 and 13, the said links 4 being extended upwardly and the links 5 being extended downwardly.

30 A sluice way 2 is provided with a set of bearings 8 and 9 secured to the lower rear and lower front ends thereof respectively, and the shafts 14 and 13, are rotatably positioned in said bearings 8 and 9 respectively, the shafts 14 and 13 being secured to the extended ends of the said links 4 and 5 respectively. The sluice 2 comprises a floor 23, an end wall 21 and the side walls 22, with the said bearings 8 and 9 secured thereto as hereinafter described.

35 The forward inner end of the sluice 2 is lined with a copper pan 27, covering the floor 23, and the walls 21—22 respectively,

the rear portion of the pan being formed with a flange 20 of a predetermined height. A box 3 composed of a floor 41 and sides 42 is detachably suspended in the pan 27 upon 60 the clips 24 allowing a predetermined space 43 therebetween, the clips 24 being secured to the box 3 and reaching around the top edges of the sluice 2. The forward half of the floor 41 in the box 3 is provided with 65 holes 40 passing therethrough of predetermined diameters.

A riffle producing member 25 is composed of two side members 26 and the upwardly and rearwardly disposed baffle plates 16 extend from the floor 23, are secured in relatively disposed grooves 18 and extend between the said side members 26, there being horizontal flanges 17 formed integral with the upper longitudinal edges of the respective plates 16, said flanges 17 being secured to the members 26 by screws 19 through the portions of the flanges 44 extending over the said members 26, said members 25 being detachably positioned in the sluice 2.

40 A head member 28 is secured around the front, bottom and sides of the sluice 2 by the flanges 34, said flanges 34 being relatively formed on the member 28, a flange 33 is formed under the lower rear portion of the 45 member 28 and extends downwardly a distance, a pin 31 is horizontally extended through a bore 44 in the flange 33 by a nut 38, a head 39 is formed on the forwardly extended portion of the bolt 31 and a spring 29 is positioned in compression between the said head 39 and its flange 33. A yoke 35 is formed in the head member 28 to support a joint 36 disposed a distance forwardly from the said flange 34. A connecting rod 50 32 is formed with a shank 45, a collar 46 secured on said shank, a bearing member 47 on the forward end thereof, and a nut 37 adjustably mounted upon the rear end thereof. The said shank 45 is operatively positioned in the joint 36 and the collar 46 bears upon the outer face of said joint, and a spring 30 is in turn mounted in compression between the joint 36 and the said nut 37.

45 The standard 10 is composed of a table 68 connected between the right and left sides of the frame 1, the central upper portion of which is formed with a longitudinal way 58. A head 59 is formed with a longitudinal way 60 positioned in alignment with said way 58, and the head 59 being secured in place by the pins 61 as shown in Figure 7.

The blocks 62 are slidably positioned between the said ways 58 and 60 by being clamped together opposite the shoulders 69 in the shafts 63 and 64. The bearing 47 of the connecting rod 32 is operatively mounted on the shaft 63 between the ways 58 and 60, and the bearing 56 is operatively mounted on the shaft 64 between the said ways 58 and 60, the bearing 56 being integral with one end of the connecting rod 55, and the straps 71 are integral with the opposite end thereof.

The bearings 57 are formed on the front upper end of the standard 10, a shaft 54 is rotatably mounted in the bearings 57 and an eccentric head 70 is secured to the said shaft 54 in alinement with the connecting rod 55.

A motor 65 is secured to the front lower end of the frame 1 with its pulley 72 positioned in alinement with the tight and loose pulleys 67, said pulleys 67 being mounted upon the shaft 54.

A receptacle 51 is formed with legs 73 to be secured to the frame 1 and the upright 11 by bolts 74, and a pipe 53 is connected to the lower end thereof, and a bracket 52 is removably fitted into the receptacle 51.

The hereinbefore described sluiceway 2 and box 3 are provided with relatively positioned lugs 50 and 49 respectively, to receive a lock 48 as shown in Figure 3.

A bumper 75 is formed on the upper rear portion of the standard 10 in alinement with the head 39 of the hereinbefore described pin 31.

Clamps 80 are secured to the sides 22 of said sluice 2 upon bolts 79 in alinement with the top edge of the riffle side members 26.

A set of lugs 49 and 50 are formed on adjacent faces of the box 3 and the sluice 2 to receive a lock 48 as shown in Figure 3.

The hereinbefore described bearings 15 are secured slidably in longitudinal slots 76 by the set screws 77 and 78 in the rear and front ends of said slots 76 for regulating the lift and stroke of the sluice and riffle mean.

When it is desired to amalgamate and concentrate ores from a mill or a placer bed the said ores are first delivered into the box 3 through a conveyor means, not shown, the motor 65 being in operation rotates the shaft 54 in its bearings 57 by the pulley 72, when the belt 66 is on the right pulley 67^b, by first shifting the said belt from the loose pulley 67^a in the customary manner.

The rotary movement of the shaft 54 in turn rotates the cam 70 within the connecting rod straps 71, thus oscillating the connecting rod 55, the bearing 56 and the shaft 64 respectively, the shaft 64 being secured between the blocks 62 cause the said bearing 56 to rotate on the shaft 64. The oscillating movement of the rod 55 thus causes the blocks 62 to run back and forth between their ways 58 and 60 and in turn pushes the

shaft 63 with the bearing 47 and its shank 45 back and forth by allowing said shank 45 to compensate its movements with the head 28 within the joint 36 between the collar 46 and the spring 36. The compression of the spring being adjusted by the nut 37 to derive the required absorption of the vibratory stresses between the shank 45 and the head 28 when pulling the said head forwardly. When the head 28 is being pulled forwardly as hereinbefore described, the head 39 on the pin 31 will strike the bumper 75 with sufficient force to shift the materials in the box 3, pan 27, and sluice 2 respectively, by causing the spring 29 to be compressed between the said head 39 and flange 33, and the unbalanced forces between the springs 29 and 30 are equalized by the movements of the pin 31 and shank 45, within the bore 44 and joint 36, respectively. The oscillatory movement of the head 28 causes the sluice 2 to move back and forth upon its bearings 8 and 9, said bearings being suspended upon the links 4 and 5 by the shafts 14 and 13 respectively, and the links 4 and 5 are in turn supported by the shafts 12 and 15 within their bearings 6 and 7 respectively.

When it is desired to lengthen the back and forth movement of the sluice 2, the nuts 38 and 37 are adjusted on the pin 31 and shank 45 to decrease the compression moment of the spring 29 and increase the compression moment of the said spring 30 respectively, thus when the head 28 is drawn forward till the head 39 strikes the bumper 75, the decreased moment of the spring 29 in proportion to the spring 30 will permit the said spring to remain a fuller length and by the increased length of the spring 30 between the joint 36 and nut 37 the stroke of the said sluice is likewise increased, and when it is desired to shorten the back and forth movement of the said sluice 2 the nuts 38 and 37 are in turn adjusted to increase the compression moment of the spring 30 respectively as hereinafter described.

When it is desired to lower or elevate the rear end of the sluice 2 with relation to the front end thereof the bearing 7 is shifted rearwardly or forwardly in the slot 76 by adjusting the set screws 77 and 78, respectively, as shown in Figure 8.

To assemble my sluice 2, pan 27, box 3 and riffle apparatus 25, the pan 27 is placed flush with the front end of the sluice 2, and the box 3 is lowered into the pan 27 with the catch 84 and lugs 49-50 in position to be secured in place by the lock 48 as shown in Figure 3, and the riffle apparatus 25 is in turn clamped flush to the floor 23 between the side walls 22 by holding the side members 26 securely by the clamps 80 upon the bolts 79. The hereinbefore described sluice assembly 1 being of a construction suitable

for use on a concentrating table of the present type.

With the hereinbefore described adjustable operation of my machine valuable minerals may be amalgamated and concentrated by depositing the ores from a mill or placer bed through a suitable conveyor means, not shown, into the box 3 with a predetermined flow of water, and the hereinbefore described back and forth movement of the box 3 packs the pulp from said ores at 81 and the water flow in turn washes the said minerals and a percentage of the pulp 81 through the holes 40 over mercury 85 placed in the bottom of the pan 27, thus the valuable minerals, preferably gold, are amalgamated with said mercury to be removed when the bottom of the pan is filled and the amalgamation operation is renewed by replenishing the pan with a new supply of mercury. As the back and forth movement of the machine continues the flow of water, pulp and minerals escaping the amalgamating process pass over the gates 20 into said sluice, the minerals still remaining in the pulp are again subjected to the back and forth movement of the machine in the water flowing over the baffle plates 16, thus the minerals being of a greater specific gravity than the pulp or water of combination, the said minerals are concentrated behind the baffle plates 16 and beneath the flanges 17 as shown at 82 in Figure 4. After the amalgamation and concentration operation has taken place the overflow pulp and water is deposited into the open receptacle 51 and allowed to discharge through the drain pipe 53 to a refuse dump, not shown.

When it is desired to remove the concentrates 82 from my machine the riffle apparatus 25 is first removed from the sluice 2 by releasing the clamps 80 upon the bolts 79. The concentrates being deposited behind the said baffle plates 16 and upon the adjacent floor 23, it will be seen that the said concentrates will be permitted to lie freely upon said floor 23 to be scooped into the bucket 52, said bucket being placed into the receptacle 51 as shown in Figure 1.

Having thus described my invention what I claim is:

1. In an amalgamating and concentrating machine of the class described, a frame,

a sluice operatively mounted in said frame upon two sets of links, one set of said links being extended upwardly from said frame to the front-bottom end of said sluice, and the other set of said links being extended downwardly from said frame to the rear-bottom end of said sluice, an adjustable vibrating means adapted to regulate the vibratory movements thereof, a power transmission means connected to said vibrating means, a riffle means positioned in the rear portion of said sluice adapted to concentrate the minerals escaping in the tailings from said amalgamated ores, a pan positioned in the forward end of said sluice adapted to hold mineral amalgamating elements, a box positioned above said pan, there being an ore screening means in the forward bottom end of said box, and an adjustable shock and stroke compensating means adapted to regulate the movements of said vibratory means.

2. In an amalgamating and concentrating machine of the class described, a frame, a sluice operatively mounted in said frame upon two sets of links, one set of said links being extended upwardly from said frame to the front-bottom end of said sluice, and the other set of said links being extended downwardly from said frame to the rear-bottom end of said sluice, the second set of said links being adjustably suspended in said frame to regulate the lift and stroke of the said sluice and riffle means, an adjustable vibrating means adapted to regulate the vibratory movements thereof, a power transmission means connected to said vibrating means, a riffle means positioned in the rear portion of said sluice adapted to concentrate the minerals escaping in the tailings from said amalgamated ores, a pan positioned in the forward end of said sluice adapted to hold mineral amalgamating elements, a box positioned above said pan, there being an ore screening means in the forward bottom end of said box, and an adjustable shock and stroke compensating means adapted to regulate the movements of said vibratory means.

In testimony whereof I hereunto affix my signature.

CHARLES E. SMITH.
